United States Patent Office

Des. 227,057
Patented June 5, 1973

227,057

CHAIR

Randall P. Buhk, Wyoming, Mich., assignor to Steelcase
Inc., Grand Rapids, Mich.

Filed May 24, 1971, Ser. No. 146,608

Term of patent 14 years

Int. Cl. D6—02

U.S. Cl. D6—30

FIG. 1

FIG. 2

FIG. 3

FIG. 4

FIG. 5

FIG. 6

FIG. 1 is a perspective view of the chair;
FIG. 2 is a front elevational view of the chair;
FIG. 3 is a side elevational view of the chair;
FIG. 4 is a rear elevational view of the chair;
FIG. 5 is a top plan view of the chair; and
FIG. 6 is a bottom plan view of the chair.
My design for a chair is characterized by the contour
of the seat shell as shown in the drawings.

I claim:

The ornamental design for a chair, substantially as
shown and described.
